DESIGN FOR A PHONOGRAPH NEEDLE BOX

Carl Pfanziehl, Highland Park, Ill., assignor to
Pfanziehl Chemical Company, a corporation
of Illinois

Application April 28, 1941, Serial No. 100,670

Term of patent 14 years

To all whom it may concern:

Be it known that I, Carl Pfanziehl, a citizen of the United States, residing at Highland Park, in the county of Lake and State of Illinois, have invented a new, original, and ornamental Design for a Phonograph Needle Box, of which the following is a specification, reference being had to the accompanying drawing, forming a part thereof, in which:

Figure 1 is a plan view of the phonograph nee-

dle box showing my new design; Figure 2 is a side elevational view thereof; and Figure 3 is a sectional view of the phonograph needle box taken along the line 3 in Figure 1. The entire phonograph needle box is formed of transparent thermoplastic material.

I claim:

The ornamental design for a phonograph needle box, as shown and described.

CARL PFANZIEHL.
